UNITED STATES PATENT OFFICE

118,809

DESIGN FOR A TOY BANK

Charles A. Ambrose, Memphis, Tenn.

Application April 21, 1939, Serial No. 84,478

Term of patent 3½ years

To all whom it may concern:

Be it known that I, Charles A. Ambrose, a citizen of the United States of America, residing at Memphis, county of Shelby and State of Tennessee, have invented a new, original, and ornamental Design for a Toy Bank, of which the following is a specification, reference being had to the accompanying drawing, wherein:

I claim:

The ornamental design for a toy bank, as shown.

CHAS. A. AMBROSE.
